UNITED STATES PATENT OFFICE.

JOSEPH G. CORNELL, OF BROOKLYN, NEW YORK.

ELEVATOR.

Application filed July 1, 1922. Serial No. 572,171.

To all whom it may concern:

Be it known that I, JOSEPH G. CORNELL, a citizen of the United States, and a resident of the city of New York, borough of Brooklyn, in the county of Kings and State of New York, have invented new and useful Improvements in Elevators, of which the following is a full, clear, and exact description.

10 This invention relates to elevators and more particularly to elevators for mounting in floors or sidewalks.

15 The general object of this invention is the provision of a cheap, simple and durable elevator of the lazy tongs type provided with balancing means that may be located below the elevator cage and which is attached to the lazy tongs system.

20 A further object of the invention is the provision of a lazy tongs elevator provided with equalizers for adjusting the operating chains on the driving mechanism.

25 These objects are accomplished by slidably mounting in a frame a cage and lazy tongs system, and attaching to the lower members of the lazy tongs system chains which are positioned over the sprocket wheels fixed to a driven shaft, and mounting on the ends of the chains equalizers and balancing 30 means.

35 These and other objects of the invention will be more clearly understood from the following detailed description and accompanying drawings, in which—

Figure 1 is a section along the line 1—1, Figure 2;

Figure 2 is a front elevation;

Figure 3 is a section along the line 3—3, Figure 1;

Figure 4 is a section along the line 4—4, Figure 1.

Referring to the above-mentioned drawings, a frame, consisting of rails 10 and 11 connected at the top by plates 12 and at the bottom by a shaft 13, is shown. This frame is mounted on a foundation 14. A plurality of braces 15 are provided in conjunction with each rail to firmly support it in a vertical position. Extending inward from the rails 10 and 11 are flanges 16 and 17 with which a plurality of shoes 18 mounted on a cage 19 slidably engage.

50 A lazy tongs system is built up from two sets of hinged bars 20 and 21, pivotally mounted at their centers on shafts 22. Mounted on the ends of the shafts 22 are

shoes 23 that slidably engage the flanges 16 and 17 of the rails 10 and 11. The shoes mounted on the lower shaft 22 are not slidably mounted on the flanges 16 and 17 but are rigidly connected thereto, supporting the lowest shaft 22 in the frame. The joints connecting the members of the two different sets and the mounting on the shafts 22 would be preferably similar to those set forth in my copending application, Serial No. 571,402, filed by me June 28, 1922. Attached to the ends of the members 20 and 21 are links 24 which serve as a means for connecting chains or the like to the lower ends of the bar members.

Rotatably mounted in bearings 25 and 26, rigidly attached to the rails 10 and 11, respectively, is a shaft 13. Fixed to this shaft is a gear 28 and four sprocket wheels 29. The sprocket wheels are mounted in alignment with the lowest members of the lazy tongs system, and chains 30 which are connected to the links 24 are positioned on the sprocket wheels 29. The gear 28, mounted near the center of the shaft 13, meshes with a pinion 31 fixed to an axle 32 which is rotatably mounted in the frame 33. Another worm gear 34 is fixed to the axle 32 and meshes with a worm 35. The shaft 36 on which the worm 35 is mounted is supported by the frame 33. A coupling 37 is provided for connecting the shaft 38 on a motor 39 to the shaft 36 on which the worm 35 is mounted.

A frame 40 is mounted on the base 14 and retained in spaced relation from the rails 10 and 11 by means of plates 41. Mounted on the frame 40 are bearings 42 in which a shaft 43 is rotatably mounted. Fixed to the shaft 43 are a plurality of sprocket wheels 44 mounted in alignment with the sprocket wheels 29 on the shaft 13. The chains 30 after passing around the sprocket wheels 29 pass over the sprocket wheels 44 and extend downward, forming loops, as shown in Figure 1, the ends of the chains being connected to T-shaped plates 45 which are pivotally connected to the frame 40 at 46. A weight 47 is attached to a shaft 48 on which four sprocket wheels 49 are rotatably mounted. The weight 47 is supported in the loops of the chains 30 by engaging the sprocket wheels 49 with the chains. Thus the weight 47 moves up and down as the chains 30 are moved back and forward over the sprocket wheels 44.

The operation of this device is as follows:

When the lazy tongs system is collapsed it rests on the lowest shaft 22 which is attached to the rails 10 and 11 by pins 51. 5 The cage 19 is supported on the lazy tongs system by means of clamps 50. When it is desired to raise the cage 19, the motor 39 is set in motion and through the worm 35, worm gear 34, shaft 32, pinion 31, gear 28, 10 the shaft 13 and sprocket wheels 29 are operated. If the shaft and sprocket wheels are rotated clockwise, as seen in Figure 1, the lower ends of the members 20 and 21 are drawn together thus expanding the lazy 15 tongs system and sliding the cage 19 upward along the rails 10 and 11. As the shaft 13 and sprocket wheels 29 are rotated clockwise, as seen in Figure 1, chains 30 pass over the sprocket wheels 44, lowering the weight 47, 20 which is carried by the shaft 48 and sprocket wheels 49, the sprocket wheels 49 traveling on the chains 30. This weight serves to balance the lazy tongs system and the cage 19. If the chains 30 are not of proper length to 25 all engage the sprocket wheels 49, the equalizers 45 rotate on their pivot points 46 and thus the weight is evenly carried on all the chains. In order to lower the cage 19, the sprocket wheels 29 and shaft 13 are rotated 30 counterclockwise by reversing the motor 39. It will be seen in the figures that the balancing apparatus is located below the lowest shaft 22 which limits the downward movement of the cage 19. Thus an elevator of 35 the lazy tongs type for installation in sidewalks or floors has been provided with a balancing means associated with the lifting means and which is located beneath the cage.

I would state in conclusion that while the 40 illustrated example constitutes a practical embodiment of the invention I do not limit myself strictly to the exact details herein illustrated, since manifestly the same can be considerably varied without departing from the spirit of the invention as defined in the 45 appended claims.

Claims:

1. An elevator, comprising a frame, a lazy tongs system mounted in the frame, flexible members attached to the lower bars of the lazy tongs system, a balancing weight attached to the flexible members, and means for operating the lazy tongs system through the flexible members. 50
2. An elevator, comprising a frame, a lazy tongs system mounted in the frame for operating the cage, flexible members attached to the lower bars of the lazy tongs system, a weight carried by the flexible members for balancing the lazy tongs system and cage, means for engaging the flexible members, and means for driving said engaging means to operate the lazy tongs system through the flexible members. 60
3. An elevator, comprising a frame, a cage 65

and a lazy tongs system mounted in the frame, flexible members attached to the lower bars of the lazy tongs system, a weight carried by the flexible members for balancing the lazy tongs system, cage equalizers attached to the flexible members to compensate for the difference in length of said flexible members, and means for operating the lazy tongs system through said flexible members.

4. An elevator, comprising a frame, a lazy 75 tongs system and a cage mounted in the frame, flexible members attached to the lower bars of the lazy tongs system, a balancing weight carried by said flexible members to balance the lazy tongs system and cage, means for engaging each of the flexible members, and means for operating said engaging means to operate the lazy tongs system through said flexible members.

5. An elevator, comprising a frame, a lazy 80 tongs system and a cage mounted in the frame, a flexible member attached to each of the lower bars of the lazy tongs system, a weight carried by the flexible members serving as a balancing means, equalizers attached to the flexible members to take up the differences in length of the same, and means for operating the lazy tongs system through the flexible members.

6. In a lazy tongs elevator including flex- 85 ible members attached to the ends of the lower bars and means for operating the lazy tongs system through said flexible members, a balancing weight carried by said flexible members.

7. An elevator, comprising a frame, a lazy 90 tongs system mounted in the frame, a chain attached to the lower end of each bar of the lazy tongs system, a shaft having attached thereto a chain wheel for each chain 105 rotatably mounted in said frame, means for operating said shaft and chain wheels to operate the lazy tongs system through the chains, and a balancing weight carried by the chains.

8. An elevator, comprising a frame, a cage and a lazy tongs system mounted in the frame, a shaft having a plurality of sprocket wheels fixed theron rotatably mounted in the frame, chains attached to the lower ends of the bars of the lazy tongs system and positioned about said sprocket wheels, equalizers attached to the chains for adjusting them on the sprocket wheels, and balancing means associated with said 110 chains.

9. An elevator, comprising a frame, a lazy 115 tongs and cage mounted in the frame, a shaft having a plurality of chain wheels fixed thereto rotatably mounted in the frame, means for driving said shaft connected thereto, a plurality of chains attached to the lower bars of said lazy tongs system and positioned about said chain wheels, a second shaft having a plurality of 120

130

- chain wheels fixed thereon rotatably mounted on the frame and having the chains positioned about said chain wheels, equalizers mounted in the frame and attached to the 5 ends of the chains, the chains between said last-mentioned chain wheels and equalizers forming loops, and a balancing weight positioned in said loops.
10. A lazy tongs elevator of the class described comprising a frame, a lazy tongs system and a cage mounted in said frame, chains attached to the lower bars of said lazy tongs system, a shaft having a plurality of chain wheels fixed thereon rotatably mounted in the frame, said chain wheels engaging the chains, balancing means for the cage and lazy tongs system associated with the chains, equalizers for adjusting the chains on said chain wheels attached to the ends of the chains, and means for driving the shaft carrying the chain wheels for operating the lazy tongs system through said chains.
11. A lazy tongs elevator, comprising a cage, a lazy tongs for operating the cage, members connected to the lazy tongs, means for operating the lazy tongs through said members, and a balancing weight carried by said members through which the lazy 30 tongs are operated.
12. A lazy tongs elevator, comprising a cage, a lazy tongs for operating the cage, flexible members connected to the lazy tongs, means for operating the lazy tongs through
- said flexible members, and a balancing weight carried by the flexible members.
13. In a lazy tongs elevator having flexible members for operating the lazy tongs, balancing means comprising means for suspending loops in the flexible members, and a balancing weight for riding in the loops.
14. In a lazy tongs elevator, means for operating the lazy tongs, comprising flexible members connected to the lazy tongs, means for operating the lazy tongs through said flexible members, a support over which portions of said flexible members depend, and a balancing weight carried by the depending portions of said flexible members.
15. In a lazy tongs elevator, means for operating the lazy tongs, including flexible members connected to the lazy tongs, equalizers connected to the flexible members, means for forming depending loops in the flexible members, and a balancing weight 55 movably mounted in said loops.
16. A lazy tongs elevator comprising a frame, a cage slidably mounted in the frame, a lazy tongs for operating the cage, flexible members connected to the lazy tongs, equalizing members mounted on the frame and connected to the flexible members for adjusting the latter, means for operating the lazy tongs through the flexible members, and a balancing weight carried by the flexible members.

JOSEPH G. CORNELL.
